UNITED STATES PATENT OFFICE

GUSTAVE A. PARTEN, OF MINNEAPOLIS, MINNESOTA

CARVING MACHINE OF MULTIPLE TYPE

Application filed October 25, 1929. Serial No. 402,405.

This invention relates to a carving machine and particularly to that type of machine used for carving wood and similar material in which a plurality of articles are simultaneously carved. In such a machine a plurality of cutting tools are used which are similarly moved in unison with and in accordance with a tracer or master tool which is moved over the pattern which it is desired to reproduce. Such machines are usually adapted to cut either substantially flat or round work. It is desirable in such a machine to have the tools movable with small effort so that they can be easily and readily controlled from the master tool. In one type of such a machine a member is used extending longitudinally of the machine which member is readily movable forwardly and rearwardly in a horizontal plane and which has connected thereto a plurality of arms mounted for lateral swinging movement about vertical axes which axes are disposed adjacent said member. These arms have in some machines been connected for simultaneous movement by means comprising yokes embracing the ends of said arms.

It is an object of this invention to provide a carving machine having a plurality of arms carried by a member freely movable forwardly and rearwardly of the machine and laterally swingable about vertical axes, said arms having means pivoted to their front ends and carried thereby in which tool holding spindles are mounted.

It is a further object of the invention to provide a machine such as set forth in the preceding paragraph in which said arms have members pivoted at their front ends movable about vertical axes, said members having tool carrying spindles journaled therein and being connected by a plurality of spaced rigid rods whereby said members and rods form a beam-like structure supported at the ends of said arms.

It is more specifically an object of the invention to provide a carving machine having a member extending lengthwise thereof oscillatable about its longitudinal axis and freely movable forwardly and rearwardly in a horizontal plane, a plurality of arms carried

by said member and swingable about vertical axes, members pivoted at their central portions to the outer ends of each of said arms and extending transversely thereof and having tool carrying spindles mounted therein at each side of said arms, said latter members being connected by three rigid rods extending therethrough whereby all of said arms and members move in unison.

These and other objects and advantages of the invention will be fully set forth in the following description made in connection with the accompanying drawings, in which like reference characters refer to similar parts throughout the several views, and in which:

Fig. 1 is a plan view illustrating a portion of a carving machine;

Fig. 2 is a vertical section taken on line 2—2 of Fig. 1 as indicated by the arrows;

Fig. 3 is a vertical section taken on line 3—3 of Fig. 1 as indicated by the arrows;

Fig. 4 is a view in front elevation of a portion of the device shown in Fig. 1;

Fig. 5 is a view in front elevation of another portion of the device shown in Fig. 1;

Fig. 6 is a vertical section taken through some of the parts shown in Fig. 1 with some portion broken away;

Fig. 7 is a vertical section taken on line 7—7 of Fig. 4 as indicated by the arrows;

Fig. 8 is a vertical section taken on line 8—8 of Fig. 5 as indicated by the arrows;

Fig. 9 is a view in front elevation of the live center;

Fig. 10 is a vertical section taken on line 10—10 of Fig. 9 as indicated by the arrows, and

Fig. 11 is an end view of a bushing used.

Referring to the drawings, a portion of a carving machine of the type shown in applicant's co-pending applications S. N. 264,650, filed March 26th, 1928 and S. N. 298,902, filed August 11th, 1928 is shown. This machine comprises a member 10 shown in the form of a pipe or tube which member is mounted for oscillating movement about its longitudinal axis and is mounted on the frame of the machine for movement forwardly and rearwardly of the machine or in a direction at

right angles to its longitudinal axis and in a horizontal plane. A shaft 10a extends through member 10 and is adapted to carry ball bearings (not shown) on which member 10 oscillates; and in the carving machine illustrated in my said co-pending applications, such a corresponding shaft is supported by wheels which travel on tracks running from front to rear of the machine. In other words, the above noted member 10 and shaft 10a form portions of a carriage which is movable backward and forward by the hand of the operator above the table containing the material to be carved. The carriage could be of substantially the identical structure as that disclosed in the expired patent to Lochman 701,903, of June 10th, 1902, but the carriage shown and described in my said co-pending application differs from the Lochman carriage in some of its details.

Said member 10 has mounted thereon at spaced points vertically extending brackets 11 having concave intermediate portions engaging member 10 and secured thereto by bolts 12. Said brackets 11 have ball bearing casings in their top and bottom surfaces receiving the tapered ends of screws 13 which extend through the bottom and top portions of arms 14, said screws being held in place by jamb nuts 15. The central member 11 receives screws 13 extending through the top and bottom portions of a tracer arm 16. Arms 14 and 16 have open portions 14a and 16a respectively at their rear ends through which member 10 passes and in which brackets 11 are disposed. Each arm 14 has a flange 14b at its rear end with a vertical flat surface thereon to which is bolted a motor 17. Motor 17 is of the electrical type and has a depending armature shaft to which is secured a pulley 18. Arm 14 forward of the portion 14a has a portion forming a supporting surface and guide way for a bracket 19 and plates 20 bolted to arm 14 by the bolts 21 overlie the side portions of bracket 19 and complete the guide-way therefor. Bracket 19 has a depending hub portion in which is secured a shaft 22 on which is journaled a flanged pulley 23, said pulley being supported on a grease cup 24 formed as a nut and threaded onto the lower end of shaft 22. Shaft 22 has a nut 25 threaded onto its upper end and a grease cup 26 is screwed onto the top end of shaft 22 which will be made hollow. Bracket 19 has a depending lug 19a into which a rod 27 is threaded, said rod extending rearwardly in arm 14 through a slot 14d in a small vertical flange therein and has secured intermediate its ends a flanged collar 28 and to its rear end a flanged collar 29. A coiled compression spring 30 surrounds the rear portion of rod 27 bearing at its ends respectively against the flanges of collars 28 and 29. Collar 28 bears against the flange in which slot 14d is formed so that spring 30 tends to

move rod 27 and pulley 23 rearwardly. Arms 14 are provided with bores at their forward ends counter-bored at each end to receive ball bearing cases 31. The inner members or races of these bearings 31 are engaged by tapered ends of screws 32 and 33 extending through the top and bottom respectively of members 34 at the central portions of the latter as shown in dotted lines in Fig. 4. Arm 16 has a similar bore 16c at its front end also counter-bored to receive ball bearing casing 31 the inner recess of which receives the tapered ends of screws 32a and 33a extending through the top and bottom portions of the member 36 as shown in Figs. 5 and 8. Screws 32a and 33a are provided with jamb nuts 32b and 33b respectively. Screws 32 and 33 are provided with jamb nuts 35 and 35a respectively. The screw 33a in arm 16 is constructed and arranged to carry a chuck 37 in which will be gripped a tracer tool 38. Each member 34 has at each side thereof spaced equal distances from screw 32 vertically extending hubs 34a. These hubs have recesses 34b intermediate their upper and lower portions, which recesses open rearwardly. A portion of each hub above recess 34b is provided with a rather large opening or bore 34c receiving a flanged cup-like member 39, in which is disposed a ball bearing casing 40. A conical compression spring 41 bears at its lower end against casing 40 and at its upper end against the top of a cap member 42, the latter having a recessed lower flange fitting over flange 39 and bolted thereto by bolts 43. A grease cup 44 is shown as mounted in the top of cap 42 and an oil cup 45 is mounted in one side thereof. A spindle 46 is provided, the top of which extends through the inner race of ball bearing casing 40 and is threaded to receive a nut 47 engaging the top of said inner race. Said spindle 46 has secured thereto a flanged pulley 48 disposed in recess 34b, said spindle having a tapered portion below pulley 48 which extends through a vertically adjustable bushing 49 threaded into the lower portion of hub 34a and held in position by a jamb nut 50. The lower end of spindle 46 is threaded to receive a chuck 51 in which is clamped a carving tool 52. Pulley 48 has circumferentially spaced notches 48a in its lower flange, said notches opening downwardly and a pin 53 slidably in member 34 is adapted to be moved vertically into said notches when it is desired to hold said pulley stationary. Pin 53 has secured thereto an outwardly extending headed bolt or pin 54 extending through a vertical slot 34d in the lower portion of hub 34a. Pin 54 has a coiled compression spring 55 surrounding the same and bearing at its outer end against the head of said pin and at its inner end against a washer 56 engaging the slot of hub 34a and extending across slot 34d. Spring 55 presses washer 56 against hub 34a

to frictionally engage the same. The lower end of pin 53 rests on nut 50. The member 34 has a split lug 34e at its top central portion and a similar split lug 34f at 5 the front of each hub 34a, as well as a similar lug 34g at the bottom and rear of each hub 34a. Member 36 likewise has a split lug 36a at its top central portion, a split lug 36b at its front central portion and a 10 similar split lug 36e at its rear lower portion. All of said lugs are adapted to be contracted by screws 57. A tubular rod 58 extends through lugs 34e on members 34 and through lug 36a on member 36. A similar 15 tubular rod 59 extends through lugs 34f on members 34 and through lug 36b on member 36. Another tubular rod 60 extends through lugs 34g on members 34 and through the lug 36c on member 36. Members 34 and 36 are 20 thus rigidly connected by the rods 58, 59 and 60, said rods being clamped in the lugs through which they pass by the screws 57. Rods 58, 59 and 60, together with members 34 and 36 thus form in effect a rigid beam or 25 bar which is pivotally supported by the arms 14 and 16. Spindles 46 and the tracer tool 38 are mounted in this bar. The said member 34 may properly be called a spindle-carrier and said member 36 may properly be 30 called a tracer-carrier. Said member 34 may carry one or several spindles.

A belt 61 extends around pulley 23, then forwardly around pulleys 48 in the hubs 34a and then rearwardly and around pulley 18 on 35 motor 17.

As shown in applicant's co-pending application S. N. 298,902, the work on the carving machine is sometimes held by the centers when round work is to be made. A novel 40 construction of center for the machine is shown in Figs. 9 to 11. Referring to said figures, a portion of the frame of the machine is shown comprising a beam 65 which is provided with openings 65a in the sides thereof 45 through which openings extends a bearing 66. Bearing 66 has a flange 66a at its end and said bearing is secured to member 65 by circumferentially spaced bolts 67 extending therethrough and into member 65. Flange 50 66a is shaped as shown in Fig. 9. A shaft 68 is journaled in bearing 66 and has secured to its rear end a worm wheel gear 69 with which meshes a worm gear 70 secured to a shaft 71 which extends longitudinally of the 55 machine and is suitably driven. Shaft 68 is shown as journaled in a ball bearing 72 in the forward part of bearing 66. Shaft 68 has a collar 68a engaging the front of bearing 72 and in front of said collar is threaded for 60 a portion of its length. Said shaft also has a reduced portion 68b in front of said threaded portion. The portion 68b is surrounded by a bushing 73 which bushing is split as shown in Fig. 11 and has a groove 73a formed 65 therein opposite its split. A sleeve 74 sur-

rounds bushing 73, said sleeve at its rear end having a flange through which extends a set screw 75 engaging bushing 73 at its inner end. Another screw 76 extends through the opposite side of sleeve 74 and into bushing 73. 70 Sleeve 74 has pins 77 secured therein the centers of which lie on a diameter of sleeve 74, said pins having flat chisel like edges at their forward ends. A pin or center 78 extends axially through the end of sleeve 74, said pin 75 having a tapered and pointed outer end and having a collar 78a at the inner side of the end of sleeve 74, said pin also having a short portion projecting inwardly from collar 78a. A conical coiled compression spring 79 is disposed within sleeve 74 the outer and smaller end embracing the end of pin 78 and bearing against collar 78a and the inner and larger end of said spring bearing against the end of bushing 73. An adjusting and clamping collar 80 is threaded on the threaded portion of shaft 68 in the rear of sleeve 74, said collar having a handle lug 80a at one side and a split lug 80b at the opposite side, said split lug having a bolt 81 extending therethrough adapted to bring the portions of 80b together 90 and clamp said collar on shaft 68.

In operation of the structure shown in Figs. 9 and 10, the collar 80 will be turned on shaft 68 to bring sleeve 74 into proper 95 relation to the work. The sleeve 74 will be brought to approximate position by adjusting one of the members carrying the centers. When collar 80 is adjusted the same will be clamped in position by bolt 81. The work 100 will be pressed against pins 77 and 78, pin 78 entering the work approximately at its longitudinal axis. The work will be driven against pins 77 and 78 and if resistance to pin 78 is sufficiently great, the spring 79 105 will be compressed allowing the work to be driven against and engaged by pins 77 without splitting the work. Pin 78 often projects forwardly sufficiently so that if no yielding is provided for, the work will be split by being driven over pin 78 before it is effectively engaged by pins 77. When the sleeve 74 is in the desired position said screw 75 is tightened pressing bushing 73 tightly 110 against shaft portion 68b and connecting sleeve 74 to said shaft so that it will be driven with said shaft. Screw 76 is provided so that bushing 73 will move with sleeve 74. It will thus be seen that by the arrangement 115 of the center structure the work can be driven against the live or driving center with no danger of the work being split. The structure accommodates the necessary adjustment of the parts.

In operation the work is clamped on a 120 work table if it is flat work or is clamped between centers if it is round work; the work being in a position to be acted upon by the tools 52. The pattern which is to be copied 125 is placed under the tracer tool 38, the motor 130

17 being driven, and the spindles 46 and tools 52 are driven through the belt 61. It will be noted that this belt will be kept under proper tension by pulley 23 which is constantly urged rearwardly by spring 30. As the tracer tool 38 is moved over the pattern the tools 52 move through the same path, arms 14 and 16 swinging about the axes of screws 13 for lateral movement and member 10 being moved forwardly and rearwardly and oscillated about its axis thus giving the front and rear and vertical movement. As above stated the tools 52 and 38 are kept in permanent rigid relation to each other and to the rods 58, 59 and 60 by which they are rigidly connected. It will of course be understood that members 34 and 36 move in the bearings 31 when arms 14 and 16 are swung laterally. The motors 17 act as counter-weights for the arms 14 and 16 and parts carried thereby. The spindles 46 rotate freely in the ball bearings 40 and in the bushings 49. The latter bushing can be adjusted vertically to take up any play in the spindles. The spindles may rise slightly if necessary against the tension of spring 41. When one of the tools 52 is to be removed or replaced it is necessary to hold the pulley 48 stationary. This is done by sliding pin 53 upwardly, by taking a hold of the head of pin 54, pin 53 moving into one of the notches 48a of pulley 48. Pin 53 will remain in the position to which it is moved owing to the friction of washer 56 against the front of hub 34a.

From the above description it is seen that applicant has provided a simple and efficient structure of carving machine and one in which the spindles are effectively carried in the swinging arms and are connected so as to swing in unison. An improved and effective structure of work holding and driving center is also provided. The structure is simple and compact, the same has been amply demonstrated in actual practice and is being commercially made.

It will, of course, be understood that various changes may be made in the form, details, proportions and arrangement of the parts, without departing from the scope of applicant's invention, which, generally stated, consists in a device capable of carrying out the objects above set forth in the novel parts and combinations of parts disclosed and defined in the appended claims.

What is claimed is:—

1. A carving machine having in combination, a member extending transversely of said machine, a plurality of arms carried by said member to swing about vertical axes, a member connected to the forward end of each arm by a pivot having a vertical axis, said member extending transversely of said arms, a tool-carrying spindle mounted in said member at each side of said arm and a

plurality of horizontal rigid rods extending through said members and holding all of said members in the same position relative to said rods.

2. A carving machine having in combination, a plurality of arms mounted for horizontal swinging movement, a member at the front of each arm connected at the center to said arms for horizontal swinging movement relative thereto, a tool-carrying spindle mounted in said member at each side of said arm and rods connected to all of said members at the front and rear side of the connection of each of said members to said arms holding said members in fixed relation to said rods and in a line extending transversely of said machine.

3. A carving machine having in combination, a member extending transversely of said machine oscillatable about its longitudinal axis, an arm carried by said member and horizontally swingable relatively thereto about a vertical axis, a member pivoted at its central portion and about a vertical axis to the forward end of said arm, tool-carrying spindles mounted in said last mentioned member at either side of said arm, a pulley secured to each spindle, a motor on the rear of said arm having a pulley secured thereto, a pulley slidably mounted in said arm in front of said first mentioned member, resilient means urging said last mentioned pulley rearwardly and a belt extending around said pulley on said motor and forwardly around the pulleys on said spindles and then rearwardly around said slidably pulley.

4. A carving machine having in combination, a plurality of laterally swingable arms, said arms being oscillatable about a horizontal axis, a member pivoted to the forward end of each of said arms about a vertical axis, said members having hubs at each side of said axis, tool-carrying spindles mounted in said hubs, said members having split lugs at the forward and rear sides of said hubs, and a split lug at the rear side of said member centrally thereof and above said lugs and rigid rods extending respectively through corresponding lugs on said members, and means for clamping said rods in said lugs.

5. The structure set forth in claim 4 and a tracer arm mounted for lateral swinging, and vertical oscillating movement, a split lug at the front of said tracer arm aligned with lugs at the front sides of said hubs, split lugs at rear of said tracer arm aligned with said lugs at rear of said hubs and arms, said rods also passing through said lugs on said tracer arm and means for holding said rods in said lugs on said tracer arm.

6. In a carving machine the combination with an arm supporting extending transversely of the machine and oscillatable in the vertical plane of a plurality of arms mount-

ed on said supporter with freedom for lateral swinging motion and a plurality of spindle-carriers pivotally connected to the forward ends of said arms for lateral swinging motion in relation to said arms, a tracer arm pivoted to said supporter for lateral swinging motion, a tracer-carrier pivoted to said tracer arm for lateral swinging motion in relation thereto and rigid connections between all of said spindle-carriers and said tracer-carrier, substantially as described.

In testimony whereof I affix my signature.
GUSTAVE A. PARTEN.
